T. W. BRACHER.
Sweat-Lining Guide for Sewing-Machines.

No. 224,134.

Patented Feb. 3, 1880.

UNITED STATES PATENT OFFICE.

THOMAS W. BRACHER, OF NEW YORK, N. Y.

SWEAT-LINING GUIDE FOR SEWING-MACHINES.

SPECIFICATION forming part of Letters Patent No. 224,134, dated February 3, 1880.

Application filed October 9, 1879.

To all whom it may concern:

Be it known that I, THOMAS W. BRACHER, of the city, county, and State of New York, have invented a new and useful Improvement 5 in Sweat-Lining Guides for Sewing-Machines, which improvement is fully set forth in the following specification, reference being had to the accompanying drawings, in which—

Figure 1 represents a plan view of my attachment. Fig. 2 is a front view of details. Fig. 3 is a cross-section in the line *x x*; Fig. 1. Fig. 4 shows a "sweat" sewed by the aid of my attachment.

Similar letters indicate corresponding parts. 15 The object of my invention is to provide a sewing-machine attachment or guide whereby a lining-strip and a reed or the like inclosed in such lining-strip may be conveniently stitched to a hat-sweat or other article; and it 20 consists in certain novel combinations of parts, hereinafter fully described, and pointed out in the claims.

In the drawings, the letter *A* designates a frame suitably constructed to support the parts 25 of my attachment.

B is a folding-guide designed to act on the lining-strip, and *C* a guide for the reed. The folding-guide *B* consists of a piece of sheet metal suitably bent to lay the lining-strip upon 30 itself at one edge, and the reed-guide *C* is a tube tapering toward its tail end and extending into the folding-guide, the two guides being made to terminate at substantially similar points. At its tail end, and on the side facing the folding-guide *B*, the tubular reed-guide 35 *C* is cut away a short distance, as at *e*, whereby the reed or its substitute is permitted to lie snugly against the inner surface of the lining-strip as it emerges from the reed-guide and 40 enters the bight or fold of the lining-strip.

With the folding-guide *B* is combined a feed-gage, *D*, and also a deflector, *F*, which acts on the lining-strip as it emerges from the folding-guide, with a tendency to prevent the same 45 from moving laterally away from the gages *G* *G'* for the edges of the hat-sweat. The gage *G* is rigid, and receives that edge of the sweat to which the lining-strip and inclosed reed are sewed, the same being arranged to 50 extend under the folding-guide *B*, while the gage *G'* is a yielding one, and is at a suitable

distance away from the rigid gage to receive the opposite edge of the sweat.

As the sweat passes between the gages *G* *G'* one edge thereof is brought under and 55 parallel to the folded edge of the lining-strip and the reed, as shown in Fig. 2, and if the sewing-needle is arranged to work immediately next the termini of the gages and guides, as at *h*, Fig. 1, the lining-strip is sewed to the 60 sweat with the reed inclosed in the folded edge, as shown in Fig. 4.

The distance to which the stitch is brought from the edge of the sweat depends upon the position of the rigid gage *G*, and in order to 65 permit this distance to be varied I make said gage adjustable. To this end I fasten the rigid gage *G* to a slide-rod, *I*, which extends substantially at right angles to the gages through eyes *j* on the frame *A*, and which 70 slide-rod *I* carries a thumb-nut, *k*, engaging a stop, *l*, for moving the rod endwise, thereby setting the rigid gage *G* toward or away from the yielding gage. With the thumb-nut *k* is 75 combined a lock-nut, *n*.

In order to render the gage *G'* a yielding one, I secure the same to a slide-rod, *O*, which extends parallel to the rod *I* through eyes *p* on the frame *A*, and which carries a stop, *q*, and spring *R*, by whose action a tendency is given 80 to the gage *G'* to move in the direction of the rigid gage *G*. The stop *q* abuts against one of the eyes *p*, thereby regulating the position of the yielding gage *G'*, and said stop is made adjustable, so that the position of the yielding gage may be varied. By the action of the yielding gage *G'* on one edge of the sweat the opposite edge thereof is held within the rigid gage *G*, while the yielding gage, moreover, adapts itself to any irregularity upon the edges 85 of the sweat.

The rigid gage *G* is provided with a spring, *s*, which, in this example, is made in one piece therewith, for pressing upon the sweat, and thereby retarding the same as it passes through 90 the gages. This retarding-spring *s* may, if desired, be combined with the yielding gage *G'* instead of the rigid gage; or such a spring may be applied to both gages.

If desired, a roller turning on a vertical 100 axis may be substituted for either or both of the gages *G* *G'*.

What I claim as new, and desire to secure by Letters Patent, is—

1. The combination, in a guide for sewing hat-sweats or other articles, of a folding-guide for a lining-strip, a tubular reed-guide extending into the folding-guide and partly cut away on one side to allow the reed emerging from the reed-guide to lie snugly against the inner surface of the lining-strip, and gages for the edges of the sweat, substantially as described.
2. The combination, in a guide for sewing hat-sweats or other articles, of a folding-guide for a lining-strip, a tubular reed-guide extending into the folding-guide, a rigid gage for one edge of the sweat, a yielding gage for its

opposite edge, and means for adjusting the rigid gage, substantially as described.

3. The combination, in a guide for sewing hat-sweats or other articles, of a folding-guide for a lining-strip, a reed-guide extending into the folding-guide, and gages for the edges of the sweat, either or both having a retarding-spring, substantially as described.

In testimony that I claim the foregoing I have hereunto set my hand and seal this 4th day of October, 1879.
